J. R. MOOR

CIRCUIT CLOSER

Filed April 11, 1922

Inventor
James R. Moor

By

Herbert E. Quisen
Attorney

UNITED STATES PATENT OFFICE.

JAMES R. MOOR, OF SPOKANE, WASHINGTON.

CIRCUIT CLOSER.

Application filed April 11, 1922. Serial No. 551,629.

My present invention relates to improvements in fire alarms of the electrical, thermal, type in which an electrical circuit is normally held open through the instrumentality of a cord or cable under tension. The device or apparatus also includes an audible signal or bell within the normally open circuit, which bell or signal is operated when the cord is severed as by burning, or broken by force applied thereto. The severing of the normally taut cord permits the closing of the signal circuit, thus giving the alarm for fire, or for burglary when the apparatus is installed for the latter purpose. The alarm is adaptable for use either in homes or industrial plants and is capable of being installed with facility and at comparatively slight expense. Provision is also made for testing the installation for the purpose of ascertaining and insuring proper working conditions of the alarm system.

The invention consists in the combination and arrangement of parts as will be herein-after more fully described in detail and pointed out in my appended claim.

In the accompanying drawings I have illustrated one complete example of the physical embodiment of my invention wherein the alarm is installed for domestic use and the parts combined and arranged according to the best mode I have thus far devised for the practical application of the principles of my invention.

Figure 1 is a view illustrating in diagrammatic form, the fire alarm installed in a building.

Figure 2 is a view of the annunciator, including a signal bell, and illustrating a pull cord at the exterior thereof, as part of a testing device.

Figure 3 is a view of the annunciator or signal device with the door open disclosing the electric batteries or cells.

Figure 4 is a top plan view of the signal device.

Figure 5 is an enlarged, detail view showing the circuit maker or switch and connections.

In order to illustrate the relation of parts I have indicated a house or building 1 in which the alarm device is installed, the audible signal in this instance being a bell 2 attached at the exterior of a box or casing 3 which is the container for the battery 4. The box or casing is located at a suitable point in the house where the ringing of the

bell 2 may readily be heard, as a signal, and the alarm switch or circuit maker as also conveniently installed in the box or casing. For this purpose a base board or plate 5 is employed and located in the upper part of the casing as indicated in Figure 3. On the base board is supported a movable contact member or switch arm 6 of proper conducting material, and the metal arm is adapted to swing on the pin 7 as a pivot, the latter being secured in the base board in suitable manner. A spring 8 has one end attached to the switch arm and another end attached to the switch or base board as an anchor, and the spring, under tension, urges the switch arm to swing toward the fixed or stationary contact point 9 on the board 5. The position shown in dotted line for the switch arm indicates a closed circuit condition, brought about by the action of the spring.

The movable switch arm is held in normal condition with the circuit broken, as shown in Figure 5, by a cord 10, retained under tension, and attached at 11 to the movable switch arm. This cord is of required length to be run over certain areas, as for instance across window openings, door openings, or other similar places, and the cord is placed in position where it can be broken by opening a window or door. For thermal indications the cord is extended over areas where fire or excessive heat is likely to develop. In the former instance the cord may be severed or broken by force, while in the latter instance the cord may be burned. In stretching or installing the cord, it is extended from the switch arm and passed around anti-friction rollers as 12, or passed through fixed eyelets as 13, the required number of rollers and eyelets being employed to guide and hold the wire suspended. For special occasions and uses, combustible fuses as 14 may be interposed in the signal line or cord, which fuses will readily burn away under excessive heat and sever the cord. For holding the cord under tension, I utilize a spring 15 attached at the end of the cord, and the spring at its other end is attached to a fixed support as a nail 16. Thus the cord 10 is attached to the switch arm and extended over the area to be protected, as along walls, across ceilings, and through other spaces as required, and passes around the pulley or pulleys 12 and through the eyes 13 as at

bends or turns. After the cord has been pulled taut, with the arm 6 in position as indicated in Figure 5, the spring 15 at the end of the cord is extended to hook over the nail 16, and by means of the spring the cord is held taut as shown. If for any reason the cord is severed between the spring 15 and the switch arm, the arm is released and is free to be swung to the left by spring 8 (in Figure 5) and caused to contact with the switch point or terminal 9. The two terminals or posts 7 and 9 are connected by the respective wires 17 and 18 to the bell or signal 2, and the swinging movement of the switch arm, under impulse of spring 8 closes the circuit causing the bell to ring and give the fire alarm or burglar alarm as the case may be.

For testing the electrical connections to ascertain if the circuit may be properly closed, I utilize a second arm as 19, of conducting metal, pivoted on the post or pin 7, and normally lying against the switch arm proper. When the cord is broken this auxiliary arm 19 forms a part of the switch arm and swings with it under impulse of the spring 8. But the auxiliary arm, in addition, is capable of movement independent of the main switch arm. Thus by pulling the cord 20 that hangs outside the box 3, and is attached to the auxiliary switch arm within the box, the auxiliary arm may be swung to close the circuit, and if the electrical connections are in normal and correct condition, the signal bell will

thus be rung. The auxiliary arm thus forms an independently movable portion of the main switch arm and is adapted to close the circuit either in conjunction with the main switch arm, or independently thereof. By this testing device the cord is not disturbed but is left in normal operative position under tension of the spring, while ascertaining the condition of the electrical connections.

Thus it will be apparent that the alarm device, both as to its electrical and mechanical features may be periodically inspected and tested, and maintained in proper working condition.

Having thus fully described my invention, what I claim as new and desire to secure by Letters Patent is—

In a fire alarm a circuit maker including a pair of separable pivoted switch arms normally lying in close electrical contact and a supporting terminal post forming a single pivot for said arms, a cord attached to the free end of one of said arms and a spring attached to the cord for holding the latter under tension, a stationary terminal post in the path of movement of the circuit maker, and a pull cord attached to the free end of the other arm whereby said arms may be separated and the second arm moved independently of the first arm to contact with the stationary terminal post.

In testimony whereof I affix my signature.

JAMES R. MOOR.
